[57] **CLAIM**

The ornamental design for multi-purpose hand tool, substantially as shown.

DESCRIPTION

FIG. 1 is an elevational view of the multi-purpose hand tool of my invention from one side;

FIG. 2 is a front elevation thereof; and

FIG. 3 is an elevational view of the other side thereof. The rear elevation corresponds to the front elevation.

FIG. 1

FIG. 2

FIG. 3
